UNITED STATES PATENT OFFICE.

GEORGE N. POLING, OF SPRINGFIELD, AND HARRY L. DILLON, OF ZANESVILLE, OHIO.

VENDING MACHINE.

Application filed June 11, 1923, Serial No. 644,752. Renewed April 25, 1927.

Our invention relates to improvements in vending machines and more particularly to those intended for dispensing newspapers and magazines, the object being to provide a generally simplified and improved machine which will be reliable in operation and cannot become jammed as often results with similar machines heretofore devised.

With the foregoing in view, the invention resides in the novel subject matter herein-after described and claimed, the description being supplemented by the accompanying drawings.

Figure 1 is a front elevation partly broken away and in vertical section.

Figure 2 is a vertical sectional view cut substantially on line 2—2 of Fig. 1.

Figure 3 is a horizontal sectional view on line 3—3 of Fig. 1.

Figure 4 is a view similar to a portion of Fig. 1 but showing a different position of parts.

Figure 5 is a detail vertical sectional view showing the manner in which the latch for the entire mechanism, is released by insertion of a coin.

Figure 6 is a horizontal sectional view on line 6—6 of Fig. 4.

Figure 7 is a similar view on line 7—7 of Fig. 1.

Figure 8 is a detail vertical sectional view on line 8—8 of Fig. 5 showing the manner in which descent of the coin is arrested by a check to hold the latch in released position.

Figure 9 is a duplicate of Fig. 8 with the exception that it illustrates the coin released by the check.

In the drawings above briefly described, the numeral 1 designates an appropriate casing within which a suitable vertical magazine 2 is provided, said casing being provided with a normally locked cover 3 which may be swung upwardly however to fill the magazine. This magazine is adapted to receive a stack of rectangular plates 4 which support the newspapers or the like 5 to be vended, said plates having appropriate ribs 6 for spacing them apart sufficiently to co-operate properly with escapement mechanisms which are used for dropping the plates and the articles supported thereby, one at a time, permitting the articles to be removed through an appropriate opening (not shown) in the front of the casing, after which the plates are dropped into an appropriate re-

ceiving drawer or other container 7 in the lower portion of the casing 1.

An upper escapement mechanism is provided to normally support the stack of plates 4 as seen in Fig. 4 and to release them one at a time, permitting them to drop onto a lower escapement mechanism. At the same time the lower mechanism catches a plate dropped by the upper mechanism, it releases a previously caught plate and permits the latter to drop into the drawer 7.

The upper escapement mechanism includes lower plate supporting fingers 8 which are normally projected as disclosed in Fig. 4, said fingers being preferably disposed in pairs at opposite sides of the magazine 2. The fingers 8 are normally projected to support the stack of plates as seen in Fig. 4 and additional fingers 9 whose effective ends are spaced slightly above the fingers 8, are normally retracted as shown in the same figure, but provision is made for simultaneously retracting the lower fingers 8 to release the bottom plate 4 and projecting the upper fingers 9 to temporarily support the stack 80 of plates. In the preferred form of construction, a pair of rockable actuators 10, in the form of rock shafts, are mounted horizontally between the magazine 2 and the casing 1, said shafts having upwardly extending crank 85 arms 11 pivoted to the fingers 8 at one side of the machine and to the fingers 9 at the other side thereof, and downwardly projecting crank arms 12 similarly connected to the fingers 9 at one side of the machine and to the fingers 8 at the other side, the fingers 8 and 9 being crossed at one side of the machine. An appropriate hand crank 13 extends from one of the rock shafts 9 and passes through an arcuate slot 14 in the front 95 of the casing 1 for the purpose of turning said rock shaft, and means are provided to connect the two shafts, to produce simultaneous operation thereof. This connecting means preferably consists of a single link 100 15 whose ends are pivoted to crank arms 16 on the rock shafts 10.

The lower escapement mechanism includes stationary checks or fingers 17 at one side of the magazine 2 and upper and lower fingers 18 and 19 at the other side of said magazine, the fingers 19 being normally projected as seen in Fig. 4 to co-operate with the fingers 17 in supporting a previously dropped plate 4, while the fingers 18 are 110

retracted as shown in the same view. Simultaneously with the dropping of another plate by the upper escapement mechanism however, the fingers 18 project as seen in 5 Fig. 1 and the fingers 19 retract as shown in Fig. 1, thus simultaneously receiving the descending plate and the paper or the like supported thereby and dropping the previously caught plate into the drawer 7.

10 We prefer to mount the fingers 18 and 19 in the same manner as the fingers 8 and 9 above described, being pivoted to crank arms 20 which extend oppositely from a rock shaft or other rockable actuator 21 disposed below one shaft 10. This last named shaft and the shaft 21 are connected for operation in unison and in so connecting them we prefer to provide laterally extending crank arms 22 thereon, which are connected by a vertical link 23.

15 A suitable spring or the like 24 is provided to return all parts to normal after operation and we have shown the same connected with the lower end of a crank arm 25 depending from the shaft 21, although it might well connect with any other movable part.

20 While the operation of the parts so far described will probably be understood from the foregoing, it may be well to briefly define such operation. To this end, let it be understood that Fig. 4 shows the normal position of parts with the stack of plates 4 and papers or magazines supported on the 25 normally projected fingers 8 and we will assume that a plate 4 from which a magazine has been removed is then supported upon the fingers 17 and 19 as also shown in Fig. 4. After proper release of a locking 30 means yet to be described, the handle or crank 13 is moved from the position shown in Fig. 4 to that disclosed in Fig. 1. In so doing, the plate 4 at the bottom of the stack, is released by retraction of the fingers 8 but the remainder of the stack is temporarily held by projection of the fingers 9 as shown in Fig. 1. The released plate is 35 caught by the fingers 18 which have been projected simultaneously with projection of the above named fingers 9, this being also shown in Fig. 1. Simultaneously with projection of the fingers 18, the fingers 19 are retracted, so that the plate 4 previously held by said fingers 19 and the co-operating fingers 17, is dropped into the drawer or the like 7. When the handle 13 is now released, the spring 24 returns all parts to their initial positions so that the relation existing in Fig. 4 again takes place, the paper or magazine being now accessible for removal 40 from the machine.

45 While it will be understood that any desired coin-controlled mechanism may be used to prevent operation of the machine until a proper coin is inserted, we prefer to pro-

vide the construction shown and described, this holding means being in the present instance associated with the hand crank or handle 13, although it might well co-operate with some other movable part.

50 A pivoted gravity-applied latch 30 is provided to engage the outwardly extending portion of the hand crank 13 as shown in Fig. 4, said latch having a releasing portion 31 extending through slots in opposite sides 55 of a vertical coin chute 32. The latch may be releasable with one coin only or may require that several coins shall be inserted one after the other, according to the price of the paper, magazine or the like. To 60 temporarily hold the coin or coins 33 in the position shown in Fig. 5, thereby holding the latch 30 in a released position until the handle 13 can be operated, we provide a coin check 34 which is preferably of the 65 form shown most clearly in Figs. 6 to 9. From these views, it will be seen that the check 34 is of arched form, with one of its legs turned laterally outward as indicated at 35 for passage through any of the openings 35a in the chute 32, according to the number of coins necessary to operate the machine. The other leg of the check 34 is held by a set screw 36 in a suitable eye 70 on one end of a horizontally movable check-releasing lever 37. This lever is normally held in the position of Fig. 6 by the handle 13 but is provided with a cam 37a disposed in the path of said handle, so that movement of the latter from the position of Fig. 4 to that disclosed in Figs. 1 and 5, will move the lever 37 to the position disclosed in Fig. 7, thereby moving the check 34 to the position of Fig. 9 and releasing the coin or coins 33. When the handle 13 returns to its normal position, the latch 30 is self-applied to again hold said handle and the lever 37 is rocked by the handle to again project the part 35 of the check 34, 75 into the coin chute 32, as disclosed in Fig. 8. Thus, the entire machine is ready for the next operation.

80 By providing the construction shown and described, or a substantial equivalent thereof, a machine is provided which is comparatively simple and inexpensive, yet will be highly efficient and reliable and cannot become jammed, which is the great objection to similar machines heretofore devised.

85 As excellent results are obtainable from the details disclosed, they may be followed if desired, but within the scope of the invention as claimed, numerous minor changes may be made.

90 We claim:

1. A vending machine comprising a magazine for a stack of gravity lowered articles, an upper escapement mechanism engageable with opposed edge portions of and supporting the stack and releasing the articles one at 95

a time, a lower escapement mechanism spaced below the stack containing portion of the magazine for catching each article dropped by said upper mechanism and simultaneously releasing the article previously dropped by said upper mechanism, said upper and lower mechanisms having rockable actuators, connecting means between said actuators insuring simultaneous movement thereof, and 10 operating means for one of said actuators.

2. A vending machine comprising a magazine for a stack of gravity lowered articles, normally projected fingers at opposite sides of said magazine to support the stack, normally retracted fingers spaced slightly above said projected fingers to support the remainder of the articles when the bottom article is released, a pair of rockable actuators at the sides of said magazine connected 20 with said upper and lower fingers for oppositely moving them, additional oppositely movable fingers below the aforesaid fingers for simultaneously receiving an article therefrom and releasing a previously received 25 article, a rockable actuator for said additional fingers, and operating means for said actuators including crank arms on the three actuators and linkage connecting said arms to insure simultaneous movement of the actuators.

3. A vending machine comprising a housing, a vertical magazine arranged in the housing and spaced from certain walls of the latter and having a plurality of opposed 35 openings in two walls, a pair of parallel rock shafts in the space between the magazine

and housing, longitudinally spaced crank arms on said shafts, upper and lower sets of fingers carried by the crank arms, and a stack of article-supporting plates in 40 said magazine, said sets of fingers being movable through the openings and alternately supporting the stack and simultaneously releasing singly the plates at the bottom of the 45 stack.

4. A vending machine comprising a housing, a vertical magazine arranged in the housing and spaced from certain walls of the latter and having a plurality of opposed openings in two walls, one of said two walls 50 having additional openings below those aforementioned, a horizontal shaft opposite each set of openings in the space between the magazine and housing, crank arms spaced along the shaft, upper and lower sets of fingers on the crank arms movable through said openings, connection between said shafts to permit uniform rocking of the crank arms, a stack of gravity-lowered 55 article-supporting plates in said magazine, certain of said fingers being movable through the opposed openings to support the stack thereabove and singly release the plates from the bottom of the stack, the other 60 fingers being movable through the lower openings to catch the plate being dropped and simultaneously release the plate previously dropped.

In testimony whereof we have hereunto affixed our signatures.

GEORGE N. POLING.
HARRY L. DILLON.
